UNITED STATES PATENT OFFICE.

ALFRED LETORT AND LOUIS CHAMBON, OF PARIS, FRANCE.

APPARATUS FOR COMPRESSING SUGAR OR THE LIKE.

Application filed September 13, 1921. Serial No. 500,372.

To all whom it may concern:

Be it known that we, ALFRED LETORT and LOUIS CHAMBON, citizens of the Republic of France, and residing at Paris, 123 Boulevard de la Gare, France, have invented an Apparatus for Compressing Sugar or the like, of which the following is a specification.

The present invention has for its object 10 a machine for compressing sugar, manufactured in mass, for conversion into lumps of definite weight and size, the machine being adapted to arrange the lumps in order on plates for conveyance to a drying stove.

15 It is constituted primarily by the combination, about a rotatable table pierced by socket molds of four devices serving for filling, for pressing, for evacuation of finished lumps, and for cleaning the pressing pistons.

Further, the machine carries means for regulating the capacity of the molds, and the travel of the pressing pistons to the desired height during rotation of the table.

25 The invention will be described with reference to the accompanying drawings, which are given as an example and in which:

Fig. 1 is an elevation of the machine.

Fig. 2 is a plan view of the same machine. 30 Fig. 3 is a view in cross section, made by a plane perpendicular to that of Fig. 1 and drawn to an enlarged scale.

Fig. 4 is a detail view of the compression regulating mechanism.

35 Fig. 5 is a detail view of the control mechanism for the rotatable table 1.

The machine comprises a circular table 1 provided with a number of pockets 2 (eight in number in the example represented), whose section corresponds with that of the lumps that it is desired to obtain. In each pocket a piston 3 is arranged to reciprocate with slight friction, the piston being connected by rods 4 and cross head 5 to two rollers 6 and 7 arranged one on each side of the cross-head and adapted to roll in cams which impart to them vertical movements.

45 The table 1 is rigidly connected to driving gear 8 by means of a hub 9, the gear being of the kind adapted to impart to the table an intermittent rotary movement.

This device comprises a plate 8 furnished with slots (Fig. 5) for engagement with 50 rollers 46 mounted on the control spindle 47. This spindle 47 receives its motion from

motor 48 by means of toothed wheels 49, 50 and 51. Spindle 47 is rotated continuously which engagement of one of the rollers 46 causes the plate 8 to make one-eighth of a revolution. Movement of this plate is stopped during the time that the roller is disengaged from the slot of plate 8. The plate 8 is then held stationary in position it being blocked by cam 52 and the lever 53 65 one extremity of which carries a roller 54 contacting with the cam and the other extremity of which has a finger 55 which engages in one of the slots 45. When the member 46 is in one of the slots 45 the cam 52 maintains the holding finger 55 out of contact with the plate 8. But when the finger 46 is removed from the slot of plate 8 the holding finger 55 stops all movement of the plate by entering one of the slots 45. 75 In this manner intermittent motion of table 1 is obtained.

The inner rollers 7 carried by the cross-member 5 of the rod 4 of the pressure piston engage in a circular cam way formed between the two cam parts 10 and 10' fixed respectively on the nave members 11 and 12 which are arranged so as not to turn about their common axis. The nave 12 can, however, slide vertically with respect to nave 80 11, by means of a rotary displacement of the screw 13 which is controlled by hand, for instance by means of the hand lever 14. This vertical movement of the nave 12 permits of an adjustment for ensuring uniformity in weight of the lumps, as the density varies, by increasing or diminishing, according to circumstances, the volume of the mass introduced into the pockets 2. 85 90

The manufactured mass is distributed by 95 means of a hopper 15 disposed at the rear of the machine and immediately above the table 1. In the interior of the hopper are mounted two inclined kneading devices 16, 17 which receive a continuous rotary movement and turn in opposite directions, they are arranged in such a way that the inclination of their blades forces the sugar in a manner to fill successively the pockets 2 of the table 1 as each of them presents itself 100 105 below the hopper 15.

While a pocket is being filled with the manufactured mass the piston 3 of that pocket is retained in its lowered position by the part 10' of the cam 10, 10'. It is this 110 position that determines the quantity of the manufactured mass admitted to the pocket,

which quantity can be regulated, as has been mentioned above, by raising or lowering the nave 12, which slides on nave 11 and constitutes the support for the part 10 of the 5 cam.

The other part 10 of the cam is supported by the nave 11 which is fixed and remains immovable. This cam positions the wheels 7 at an invariable height in front of the 10 compressing means which insures manufactured lumps of a uniform thickness.

For effecting the compression of the manufactured mass as soon as it has been introduced into a pocket, the machine is provided with the parts mentioned below. A 15 filled pocket, in consequence of the displacement of the table 1 comes into a position immediately below a compressing cushion 18 which closes it completely by being superposed. Moreover, below the piston rods 4 and the cross-head 5 is disposed an arrangement of bent levers 19, controlled by a connecting rod 20 operated by means of a roller lever 21 and cam mechanism 22. This 20 control system imparts to piston 3 a vertical movement thereby compressing the sugar in the pocket between the piston and the cushion 18.

For effecting the discharge of the lumps 30 after being compressed as described, the machine comprises the following means. The lump compressed in a pocket moves into the receiving position by reason of the movement of table 1. When it is in this position, 35 the outer roller 6 becomes engaged in a groove formed in the lever 23, controlled by a system of cams and the lump receives a vertical rising movement so that its lower face assumes a position at a level slightly 40 above that of an auxiliary conveying table 24. The lump is then pushed on to this table by a blade 25 controlled by a system of cams and by means of intermediate connecting rods and levers 26, 27, which are capable 45 of parallel motion and cause the blade 25 to slide lightly in contact with the face of the lump during the displacement of the latter.

The table 24 has the form of a regular 50 polygon whose sides correspond in number with the number of pockets on table 1, that is to say eight in the illustrated example. It receives an intermittent rotary motion, which is communicated to it by the wheel 55 24', for the purpose of moving the lump from the position *a* to the position *b* opposite and immediately above the conveyor plates.

When the lump has arrived in the position 60 *b*, a blade 28, controlled by the same system of cams as the blade 25 above referred to, pushes the lump on the conveyor plates which are carried along by an endless chain 29 actuated with a continuous movement.

65 The chain is provided with claws or abut-

ments 30 which impel the plates against which are distributed the lumps *L*, and is controlled by the drums 31, 32 at the left hand end of the machine (Fig. 1) and above drum 31, is arranged a magazine 33 serving 70 for the distribution of the plates 34. This magazine comprises four vertical uprights 35 between which are piled the plates. The lowest plate in the pile is dragged by a claw or lug on the endless chain which is presented to it opposite the left hand portion of the pile. The upper plates remain between the set of uprights, the lower part of which has the clearance necessary for the passage 80 of one single plate at a time. When this plate has been removed the plate immediately above it takes its place, and the magazine automatically empties under gravitational action. The plates, as they arrive loaded with lumps *L* at the right hand end 85 of the machine (Fig. 2), are lifted by hand.

To ensure the cleaning of the pistons of the pockets, these pass in succession, between the lump discharging position and the pocket position, opposite a cleaning device 90 arranged as follows.

In the position defined above, the piston is brought level with the surface of table 1 and its upper part is then swept by the cleansing arms 36, 37, which are furnished with rubber or other strips which scrape the top end of the pistons, the arms receiving a continuous rotary movement. The arms are, moreover, adjustable vertically by 100 means of a screw device so as to apply to the tops of the pistons pressure sufficient to ensure perfect cleansing. During the rotary movement the rubber or other strips pass over a spongy cylinder adapted to keep them moist. The syrup engendered during the 105 washing operation is collected and evacuated from the pan 38.

It will be seen that the four operations

- (a) The filling of the pockets;
- (b) The compression of the lumps;
- (c) The discharge and delivery of the lumps;

(d) The washing of the piston heads, are effected simultaneously for four different 110 pockets at a time, the pockets being disposed at 90° to one another.

Having now particularly described and ascertained the nature of our said invention and in what manner the same is to be performed, we declare that what we claim is:

1. A machine for compressing sugar manufactured in mass, comprising an intermittently rotatable table, a plurality of molds spaced 90° from one another on the table, in combination with filling means for supplying sugar to the molds, pressing means for forming lumps of regulable dimension, evacuating means for placing finished lumps upon a conveyor, and cleaning means for the pressing means, the above four said 125

means operating simultaneously, certain of said means being controlled by an annular two-piece cam, one of which pieces is fixed with respect to the frame of the machine, 5 while the other is movable vertically, by the operator of the machine, the movable part being carried by a sleeve slideable on a post which supports it, a manually actuated screw, means for actuating the sleeve, and 10 screw threads on the sleeve for co-operating with the actuating means.

2. A machine for compressing sugar manufactured in mass, comprising an intermittently rotatable table, a plurality of molds 15 spaced 90° from one another on the table, in combination with filling means for supplying sugar to the molds, pressing means for forming lumps of regulable dimension, evacuating means for placing finished lumps 20 upon a conveyor, and cleaning means for the pressing means, the above four said means operating simultaneously, the evacuating means being controlled by a lever actuated by a cam mounted on the same member as the controlling means for the pressing means, and carrying a slot at its extremity receiving actuating mechanism for 25 the pressing means.

3. A machine for pressing sugar manufactured in mass, comprising an intermittently rotatable table, a plurality of molds spaced 90° from one another on the table, in combination with filling means for supplying sugar to the molds, pressing means 30 for forming lumps of regulable dimension, evacuating means for placing finished lumps upon a conveyor, and cleaning means for the pressing means, the above four said means operating simultaneously, the evacuating 35 means comprising an auxiliary, intermittently movable, octagonal table, a paddle for pushing finished lumps onto the table,

a conveyor having conveyor means, and a second paddle for pushing the finished lumps onto the conveyor means. 45

4. A machine for pressing sugar manufactured in mass, comprising an intermittently rotatable table, a plurality of molds spaced 90° from one another on the table, in combination with filling means for supplying sugar to the molds, pressing means for forming lumps of regulable dimension, 50 evacuating means for placing finished lumps upon a conveyor, and cleaning means for the pressing means, the above four said means operating simultaneously, the evacuating means comprising a distributing box for transporter plates, plates in said box, and an endless chain having means for grasping said plates. 55

5. A machine for pressing sugar manufactured in mass, comprising an intermittently rotatable table, a plurality of molds spaced 90° from one another on the table, in combination with filling means for supplying sugar to the molds, pressing means for forming lumps of regulable dimension, 60 evacuating means for placing finished lumps upon a conveyor, and cleaning means for the pressing means, the above four said means operating simultaneously, the cleaning means comprising rubber tipped arms for passing over the surfaces of the pressing means, the arms being adjustably mounted. 65

In testimony whereof we have signed our names to this specification in presence of two witnesses.
